UNITED STATES PATENT OFFICE.

MURRAY B. LEETE, OF WALLINGFORD, CONNECTICUT, ASSIGNOR TO R. WALLACE & SONS MFG. CO., OF WALLINGFORD, CONNECTICUT, A CORPORATION.

DESIGN FOR A SPOON, FORK, OR SIMILAR ARTICLE.

41,297.

Specification for Design.

Patented Apr. 11, 1911.

Application filed January 20, 1911. Serial No. 603,764. Term of patent 7 years.

To all whom it may concern:

Be it known that I, MURRAY B. LEETE, a citizen of the United States, residing at Wallingford, in the county of New Haven and State of Connecticut, have invented a new, original, and ornamental Design for a Spoon, Fork, or Similar Article; and I do hereby declare the accompanying drawing to be a full, clear, and exact illustration of the same, and which said drawing constitutes part of this specification, and represents a face view of a spoon, fork, or similar article embodying my design.

I claim:

The ornamental design for a spoon, fork or similar article, as shown.

MURRAY B. LEETE.

Witnesses:

CHAS. E. ALLEN,
H. L. WALLACE.
